UNITED STATES PATENT OFFICE.

JOSEPH S. DUNCAN, OF CHICAGO, ILLINOIS, ASSIGNOR TO ADDRESSOGRAPH COMPANY,
OF CHICAGO, ILLINOIS, A CORPORATION OF ILLINOIS.

PRINTING DEVICE.

1,026,250.

Specification of Letters Patent.

Patented May 14, 1912.

Application filed September 29, 1910. Serial No. 584,420.

To all whom it may concern:

Be it known that I, JOSEPH S. DUNCAN, a citizen of the United States, residing at Chicago, in the county of Cook and State 5 of Illinois, have invented new and useful Improvements in Printing Devices, of which the following is a specification.

This invention relates to that class of printing devices in which a printing plate 10 is carried by a frame and which is adapted to be stored in accordance with a card index system and run through an addressing or other printing machine for taking an impression therefrom.

15 The devices are used principally for printing addresses and are generally employed by those who send out many bills regularly to the same customers, such as gas companies, electric light companies and telephone companies. They are also largely used by publishers and other concerns that have large mailing lists.

When a change in address occurs it has been customary heretofore to prepare a new 25 printing plate and it is desirable to reduce the cost of thus maintaining the lists up to date by avoiding the necessity of replacing the entire plate. In the case of a telephone company, for example, it may be that a telephone number will be permanently located 30 at a certain address, and thus if the subscriber moves away from that address it would be sufficient simply to change the name of the old subscriber for that of the 35 new subscriber without changing the remainder of the printing device, or the telephone number may be made the permanent feature of the printing device and the address the detachable feature. This may occur in many other uses of these printing 40 devices but the example above noted will be sufficient to indicate the purpose of my invention.

In my application, Serial No. 573,591, 45 filed July 25, 1910 I have disclosed one way to obtain the results herein sought by providing a sectional printing plate so that a part thereof can be replaced and the other part continued in use. But I have discovered 50 that the same results can be obtained by making the permanent part of the printing form on the frame itself and the changeable part on a removable plate adapted to be secured in the frame in proper relation 55 to the permanent part of the form.

The object of my invention is to reduce the expense of maintaining a system of printing devices of this general character by providing for the renewal of so much only of the printing device as is necessary 60 when changes occur. And a further object of the invention is to provide the frame with an integral and permanent printing form and with means for removably securing a printing plate on the frame in proper 65 relation to the permanent printing form. And a still further object of the invention is to arrange the printing face of the type characters of the permanent printing form on the frame in the same plane with or in 70 a different plane from the printing characters on the plate when arranged in the frame.

In the accompanying drawings Figure 1 is a front view of my invention showing 75 the permanent printing form on the frame in a lower plane than the printing form on the plate. Fig. 2 is a similar view showing the permanent printing form in the same plane with the form on the plate. Fig. 3 80 is a sectional view on the line 3—3 of Fig. 1. Fig. 4 is a detail sectional view on the line 4—4 of Fig. 2. Fig. 5 is a transverse sectional view on the line 5—5 of Fig. 1. Fig. 6 is a transverse sectional view on the 85 line 6—6 of Fig. 2. Fig. 7 is a detail view of the printing plate.

The frame 8 is provided at its ends with spacing flanges 9 of suitable character and at its top and bottom with beads 10 and 11. 90 A card 12 is removably held in a card receiving space beneath the bead 10 and the lips 13 by end stops 14, or in any other suitable manner.

The printing plate 15, in the embodiment 95 of the invention selected for illustration, has a complete address stamped in relief thereon and is held in a printing plate receiving space beneath the bead 11 and the lips 16 by the tongue 17 which is depressed sufficiently to engage an opening 18 in the frame (Fig. 4). After the plate has been arranged in place in the frame the tongue can be readily bent downward sufficiently 100 to make proper engagement with the opening in the frame, and it can likewise be readily pressed upward to permit the plate to be removed from the frame whenever 105 desired.

In the two embodiments of the invention 110

illustrated in Figs. 1 and 2, the card and plate receiving spaces are separated from each other sufficiently to provide an intermediate space for the permanent form which is 5 stamped in relief directly in the frame. In Fig. 1 the form 19 is stamped up from the frame and its printing face lies in a plane below that of the form on the plate (Fig. 5.) However, the planes of the printing 10 faces of the printing characters of the frame plate and of the printing plate are disposed for making substantially simultaneous impressions. In Fig. 2 a panel 20 is pressed up on the frame and the permanent form 21 is 15 stamped up from this panel so that the face of the permanent form lies in the same plane with the face of the form on the plate. In the construction of Fig. 2 the lips project from the upper edge of the panel and the 20 lower edge of the panel forms a stop which is engaged by the upper edge of the plate 15. In the construction of Fig. 1 the lips 13 and 16 are sufficiently removed from the permanent form 19 to be clear of the mechanism of the addressing machine and the frame is provided with a stop 22 which operates with the lip 16 to prevent upward 25 movement of the plate.

Taking a printing device for use by a telephone company, for example, the telephone 30 number and rate is shown in the drawings as the permanent form stamped from the frame and the subscriber's address is provided on the plate so that the frame, which 35 is a permanent part of the device, may be used indefinitely and the plate and card renewed as often as required. Obviously the particular forms of the frame and on the plate may be changed as desired without 40 departing from the invention and in the example shown the address might be made the permanent form on the enlarged panel and the telephone number the renewable form on the narrow plate.

My invention provides a simple method 45 and means for reducing the cost of maintaining lists of names in the form of printing devices especially where frequent changes are required in the printing form.

What I claim and desire to secure by Letters Patent is:

1. A printing device comprising a frame having an elevated panel stamped therein and provided with a permanent printing form, means upon the frame at one side of 55 the panel for holding a printing plate, and means upon the frame at the opposite side of the panel for holding a card, substantially as described.

2. A printing device comprising a frame 60 plate having permanent type characters stamped in an intermediate portion thereof, card-retaining means stamped up from the plate at one side of the permanent printing characters, printing plate retaining means 65 stamped up from the plate at the other side of the permanent printing characters, and a detachable printing plate engaged with the printing plate retaining means, said detachable printing plate having printing 70 characters stamped up therefrom, the planes of the printing faces of the printing characters of the frame plate and of the printing plate being disposed for making substantially simultaneous impressions. 75

3. A printing device comprising a frame having a central longitudinal elevated panel provided with a permanent printing form stamped in relief on the elevated face of the panel, means upon the frame at one side of the panel for holding a printing plate, and means upon the same side of the frame and at the opposite side of the panel for holding 80 a card, substantially as described.

JOSEPH S. DUNCAN.
